ADJUSTABLE LEG REST

Helen L. Arnott, Phoenix, Ariz.

Filed Nov. 12, 1959, Ser. No. 58,324

Term of patent 14 years

(Cl. D15—8)

Fig. 1 is a front perspective view of an adjustable leg rest showing my design;

Fig. 2 is a side elevational view of the article in its intermediate position; and

Fig. 3 is a side elevational view of the article in its lowest position.

I claim:

The ornamental design for an adjustable leg rest, as shown.
